REDUCTION GEARING

Benjamin F. Schmidt, Los Angeles, Calif.

Application August 8, 1944, Serial No. 548,517

9 Claims. (Cl. 74—789)

1

My invention relates to reduction gearing and has particular reference to a gearing which may be readily adapted to provide either a high speed or a low speed transmission from a source of power or for a hoist or similar device.

In many industrial applications it is desirable to provide for a high speed and a low speed transmission which may be readily selectable, dependent upon the character of the work to be done. For example, in many applications of small industrial electric motors it is desirable that the motor operate to produce one speed of transmission for the driving of certain portions of a machine while other portions of the machine are required to be driven at a different speed but coordinated with the speed of the first drive.

It is therefore an object of my invention to provide a gear reduction unit which may be readily employed for the purpose of producing a differential between two transmissions to permit the same motive power means to provide two different speeds of transmission.

Another object of my invention is to provide a reduction gearing of the character described, which may be readily and simply manufactured and may be embodied as an integral part of the assembled prime mover or motor.

Another object of my invention is to provide a reduction gearing of the character described which is readily adapted for use in either a power or a chain hoist to permit the application of force through a substantially direct drive for the purpose of bringing the hoist hook into taut relation with the load and thereafter the power may be applied through a reduced gearing for the purpose of raising the hook and the load from that point.

Other objects and advantages of my invention will be apparent from a study of the following specifications, read in connection with the accompanying drawings, wherein

Fig. 1 is vertical sectional view taken through a reduction gearing constructed in accordance with my invention and illustrated as being assembled as an integral part of the end-bell of an electric motor;

Fig. 2 is a transverse sectional view taken along line II—II of Fig. 1;

Fig. 3 is a detail view of one of the transmission pinions which I employ in my reduction gearing;

Fig. 4 is a detail view of the supporting frame member for carrying the pinions;

Fig. 5 is a detail view of a modified form of pinion which may be employed in my reduction gearing;

2

Fig. 6 is a vertical sectional view of a modified application of the same form of reduction gear as that illustrated in Figs. 1 through 4 but showing the same as applied to a chain actuated hoist; and

Fig. 7 is a vertical sectional view taken along line VII—VII of Fig. 6.

Referring to the drawings, I have illustrated my invention as being applied to an electric motor 1, the housing 2 of which is provided with an end flange 3, to which may be attached the usual end-bell. The armature 4 of the motor is illustrated schematically as operating in conjunction with the field poles 5 surrounded by exciting coils 6 as in the usual electric motor construction. The armature 4 is provided with a shaft 7, from which power arrived from the motor is to be taken off.

In place of the usual end-bell of the motor providing merely a bearing for the shaft 7, I substitute a special end-bell 8, which end-bell has an internally formed recess 9 carrying a bearing 10 and providing a suitable housing within which may be received the reduction gearing constructed in accordance with my invention.

25 The reduction gearing comprises essentially a tubular drive shaft 11 provided, as indicated at 12, with worm teeth intermeshed with a pair of pinions 13 and 14. These pinions are rotatably mounted upon stub shafts 15 upon a supporting structure 16, illustrated particularly in Fig. 4, in such manner that rotation of the tubular shaft 7 relative to the supporting frame 16 will cause the pinions to rotate about their stub shafts 15.

By referring particularly to Figs. 2 and 3, it will be observed that each of the pinions is provided with an extension, which in turn has formed upon it a conically shaped worm thread 17 adapted to mesh as indicated in Fig. 2 with internally formed teeth 18 upon a ring 19. Thus as the pinions 13 and 14 are rotated they will cause rotation of the ring gear 19. However, by securing the ring gear 19 against rotation relative to the end-bell of the motor, as by a key 20, the result of the rotation of the pinions 13 and 14 will be to cause the supporting frame 16 to rotate relative to the end-bell 8 and relative to the motor shaft 7. The relative rates of rotation of the motor shaft 7 and the frame 16 will be greatly different, the effect being to produce a differential motion between these two shafts.

40 By properly selecting the number and pitch of the worm teeth upon the drive shaft 11 and the diameter and pitch of the pinions 13 and 14 and also the pitch of the worms 17, substantially any desired relative speeds of rotation may be obtained between the motor shaft and the frame.

As will be observed from an inspection of Figs. 1 and 4, the frame 16 is provided with a forwardly extending portion 16a which provides a sleeve shaft from which power may be taken off.

Thus by providing a pulley 21 upon the sleeve shaft 11 keyed thereto as indicated at 22 (the sleeve shaft 11 being keyed as indicated at 23 to the motor shaft 7), the pulley 21 will be operated at the normal rate of rotation of the motor. By providing a second pulley 24, keyed as indicated at 25, to the sleeve shaft formed by the extension 16a, the pulley 24 may be rotated at some different rate of speed dependent upon the selection of the gearing as described above.

If desired, the frame 16 may be provided with both radial and thrust bearings indicated at 26, 27 and 28 to reduce the friction of rotation of this frame relative to the sleeve shaft 11 and the end-bell in which it operates, the bearings 27 and 28 being preferably held in place by spring washers 29 snapped into grooves formed in the end-bell and the sleeve shaft 11, respectively. Similarly, the main bearing 10 for the motor shaft 7 may be held in place by means of a snap ring 30 seated in a radial groove formed upon the end-bell structure.

In view of the fact that there will undoubtedly be considerable bending thrust exerted upon the extreme outer end of the extension 16a of the frame, I prefer to provide a needle roller bearing 32 interposed between the sleeve shaft 11 and the extension 16a. Likewise needle bearings 33 and 34 may be provided for each of the pinions 13 and 14, as illustrated in Fig. 2, while a thrust bearing 35 may be provided also for each of these bearings.

A novel manner in which the stub shafts 15 may be secured in the supporting frame 16 is illustrated in Fig. 2 as comprising forming laterally extending bores completely through the piece of metal or other material of which the frame is made, into which the stub shafts 15 may be inserted and held in place by cross pins 36.

By employing the recess 9 in the end-bell of the motor as the housing into which the reduction gearing may be inserted, it will be apparent that the entire structure may be inserted or removed as a unit by merely removing the end washer 37 which is employed to retain the assembly within the recess. This facilitates repair by permitting the ready removal of any reduction gearing which may be out of order and the immediate substitution of a duplicate assembly with a minimum of effort and loss of time, and further facilitates the initial assembly by permitting the entire gear unit to be made up as an assembly independent of the motor and then to be assembled upon the motor merely by insertion in the recess and securing the washer to the end-bell.

When the reduction gear is to be employed for driving a relatively large ring gear upon which great loads are imposed, I prefer to use a double worm ended pinion 13 as shown in Fig. 5, which permits the distribution of the driving forces over additional areas of gear teeth.

In Figs. 6 and 7 I have illustrated a modified application of the same essential reduction gearing structure as that illustrated in Figs. 1 through 4, the adaptation being to a chain hoist wherein the hoist is supported upon a suitable hook 49 which engages a yoke-like frame 41. The frame 41 has a transverse bore 42 formed therein, into which is inserted the pinion supporting frame 43,

corresponding in all essential respects to the frame 16, heretofore described.

The frame 43 is provided with a longitudinal bore 44, through which extends a power shaft 45, one end of which may be secured to a pulley 46 provided with chain sprocket recesses 47 or, as will be understood by those skilled in this art, the shaft 45 may be coupled in any suitable manner to an electric or other type of motor which will cause rotation of the shaft 45.

The shaft 45, like the sleeve shaft 11, is provided with a worm thread 48 which meshes with a pair of pinions 49 and 50, respectively, these pinions being mounted upon stub shafts 51 mounted in the frame 43, in the same manner as was described for the stub shafts 14. Again the pinions 49 and 50 are provided with extensions which are formed as conical worms 52 meshing with internal teeth 53 upon a ring gear 54. In this form of my invention, the ring gear 53 is not fixed against rotation but is employed as the power transmitting portion of the gearing as by providing upon its exterior a radially extending pair of flanges 55 which form a chain sprocket over which the hoisting chain of the hoist extends.

Thus by rotating the shaft 45, either by means of the pulley 47 or a motor (not shown), the resultant rotation of the pinions 49 will cause a rotation of the ring gear 53 at a much reduced speed and therefore with great mechanical advantage.

Again, as with the form of the gearing illustrated in Figs. 1 through 4, each of the parts may be suitably supported in roller, thrust or needle bearings as illustrated in Figs. 6 and 7.

In order to permit the ready and rapid movement of the hoisting hook at the end of the hoisting chain, I prefer to provide a means for selectively permitting rotation of the pinion supporting frame 43. This may be readily accomplished by providing a pin 56 slidable through a vertically extending opening 57 in one of the legs of the yoke, the upper end of the pin 56 being adapted to enter a radially extending socket 58 formed in the frame 43. The pin 56 is normally urged upwardly by means of a spring 59 but may be withdrawn whenever it is desired by means of a chain or pull cord 60.

Thus if the pin 56 is disengaged from the bore 58 and the pulley 47 is rotated, the relative friction between the parts will cause gear 53 to be rotated at the same speed as the shaft 45 until a load is placed upon the hoisting chain. When this occurs the hoisting hook and chain are then in a substantially taut relation with respect to the load that is to be hoisted and release of the chain 60 will permit the pin 56 to be urged upwardly against the surface of the frame 43. Thereafter rotation of the shaft 45 will cause the frame 43 to rotate until the bore 58 is realigned with the pin 56 and the pin is permitted to reenter the socket 58. At this time the parts are then in their locked up relation so that further movement of the shaft 45 will cause rotation of the ring gear 53 at the reduced speed and with the mechanical advantage necessary to lift the load.

If desired, a chain guard 61 may be mounted upon the yoke frame 41, as by means of screws 62, the guard preferably being formed so as to extend immediately above the periphery of the pulley or sprocket 46 so as to prevent the chain from being inadvertently removed therefrom. An extension arm 63, which may be formed integrally with the guard 61, is adapted to extend

across the yoke immediately above the periphery of the chain sprocket 55 to perform a similar function for this sprocket, the extreme end of the extension arm 63 being secured in any suitable manner as by means of a screw 64.

It will be observed from the foregoing description that my reduction gearing can be readily and simply manufactured and operated with a minimum of frictional loss between the teeth of the various gears. An important feature of this construction is the fact that the ring gear is in effect an internal spur gear since the teeth thereon extend substantially parallel with the longitudinal axis of the ring gear, facilitating the construction of such gear and providing a minimum amount of friction with the worm 17 on the pinion.

It will be apparent from the foregoing that I have illustrated a reduction gearing which is extremely simple in its construction, which may be readily manufactured and assembled in mass production, and which provides for a substantially unlimited relation between the operating speeds of a driving and a driven member.

While I have shown and described the preferred embodiment of my invention, I do not desire to be limited to any of the details of construction shown and described herein, except as provided in the accompanying claims.

I claim:

1. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft; a pair of gears mounted for rotation on said frame member on opposite sides of said shaft, each of said gears comprising a worm wheel meshed with said worm thread and having a cone shaped extension extending beyond said worm wheel and carrying a worm thread meshed with said internal gear teeth; means for holding one of said members stationary; and power takeoff means connected to the other of said members.

2. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft; a pair of gears mounted for rotation on said frame member on opposite sides of said shaft, each of said gears comprising a worm wheel meshed with said worm thread and having a cone shaped extension extending beyond said worm wheel and carrying a worm thread meshed with said internal gear teeth; means for holding one of said members stationary; power takeoff means connected to the other of said members; and a second power takeoff means connected to said shaft.

3. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft including an anti-friction bearing interposed be-

tween said frame member and said shaft; a pair of gears mounted for rotation on said frame member on opposite sides of said shaft, each of said gears comprising a worm wheel meshed with said worm thread and having a cone shaped extension extending beyond said worm wheel and carrying a worm thread meshed with said internal gear teeth; means for holding one of said members stationary; and power takeoff means connected to the other of said members.

4. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft; a pair of gears mounted for rotation on said frame member on opposite sides of said shaft, each of said gears comprising a worm wheel meshed with said worm thread and having a cone shaped extension extending beyond said worm wheel and carrying a worm thread meshed

25 with wheel and carrying a worm thread meshed with said internal gear teeth; means for holding said ring gear member stationary; and power takeoff means connected to said frame member.

takeoff means connected to said frame member.

5. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft; a pair of gears mounted for rotation on said frame member on opposite sides of said shaft, each of said gears comprising a worm wheel meshed with said worm thread and having a cone shaped extension extending beyond said worm wheel and carrying a worm thread meshed with said internal gear teeth; means for holding said frame member stationary; and power takeoff means connected to said ring gear member.

30

35

40

45 6. In a reduction gear unit, the combination of: an inner shaft having a worm thread thereon; a frame member surrounding said shaft; a ring gear member surrounding said frame member and having internal gear teeth; means 50 mounting said members for relative rotation about the longitudinal axis of said shaft and mounting one of said members for rotation relative to said shaft; a pair of gears mounted for rotation on said frame member on opposite sides 55 of said shaft, each of said gears comprising a worm wheel meshed with said worm thread and having a cone shaped extension extending beyond said worm wheel and carrying a worm thread meshed with said internal gear teeth; 60 means for holding said ring gear member stationary; power takeoff means connected to said frame member; and a second power takeoff means connected to said shaft.

7. In a reduction gear unit, the combination
65 of: an inner shaft having a worm thread thereon;
a frame member surrounding said shaft; a ring
gear member surrounding said frame member
and having internal gear teeth; means mount-
ing said members for relative rotation about the
70 longitudinal axis of said shaft and mounting one
of said members for rotation relative to said
shaft; a pair of gears mounted for rotation on
said frame member on opposite sides of said
shaft, each of said gears comprising a worm wheel
75 meshed with said worm thread and having a

cone shaped extension extending beyond said worm wheel and carrying a worm thread meshed with said internal gear teeth; means for holding said frame member stationary; power takeoff means connected to said ring gear member; and a second power takeoff means connected to said shaft.

8. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft; a pair of gears mounted for rotation on said frame member on opposite sides of said shaft, each of said gears comprising a worm wheel meshed with said worm thread and having a cone shaped extension extending beyond said worm wheel and carrying a worm thread meshed with said internal gear teeth; power takeoff means connected to one of said members; and releasable means for normally holding the other of said member stationary, whereby when said releasable means is released rotation of said shaft will drive both of said members at the same speed as said shaft and when said releasable means is engaged with said other member said one member will be rotated at a predetermined but different speed relative to said shaft.

9. In a reduction gear unit, the combination of: an inner shaft having a worm thread thereon; a frame member surrounding said shaft; a ring gear member surrounding said frame member and having internal gear teeth; means mounting said members for relative rotation about the longitudinal axis of said shaft and mounting one of said members for rotation relative to said shaft; a pair of gears mounted for

rotation on said frame member on opposite sides of said shaft, each of said gears comprising a worm wheel meshed with said worm thread and having a cone shaped extension extending beyond said worm wheel and carrying a worm thread meshed with said internal gear teeth; power takeoff means connected to said ring gear member; and releasable means for normally holding said frame member stationary, whereby when said releasable means is released rotation of said shaft will drive both of said members at the same speed as said shaft and when said releasable means is engaged with said frame member said ring gear member will be rotated at a predetermined but different speed relative to said shaft.
